Filed Mar. 18, 1969, Ser. No. 16,308

Term of patent 14 years

Int. Cl. D24—03

U.S. Cl. D83—12

FIG. 1 is a perspective view of a swivel handle curette showing my new design;

FIG. 2 is a left side elevational view thereof;

FIG. 3 is a front elevational view thereof;

FIG. 4 is a right side elevational view thereof;

FIG. 5 is a bottom plan view thereof; and

FIG. 6 is a top plan view thereof.

The rear view, not shown, is the same as the front view except there is no cutout in the curette.

I claim:

The ornamental design for a swivel handle curette, substantially as shown and described.
